UNITED STATES PATENT OFFICE

96,747

DESIGN FOR A RANGE BASE

Donald L. Hadley, Mansfield, Ohio, assignor to
The Tappan Stove Company, Mansfield, Ohio, a corporation of Ohio

Application April 9, 1935, Serial No. 56,284

Term of patent 7 years

To all whom it may concern:

Be it known that I, Donald L. Hadley, a citizen of the United States, residing at Mansfield, in the county of Richland and State of Ohio, have invented a new, original, and ornamental Design for a Range Base, of which the following is a specification, reference being had to the accompanying drawing, forming part thereof, wherein the single figure is a perspective view of a range base embodying my new design.

The side of the range base which is not disclosed in the drawing is identical with the side which is disclosed.

I claim:

The ornamental design for a range base, substantially as shown and described.
